No. 709,939.

Patented Sept. 30, 1902.

C. F. THAYER.

COUCH.

(Application filed Jan. 9, 1902.)

(No Model.)

UNITED STATES PATENT OFFICE.

CLARK F. THAYER, OF ERIE, PENNSYLVANIA, ASSIGNOR TO WILCOX BROTHERS, OF JOLIET, ILLINOIS, A CORPORATION OF ILLINOIS.

COUCH.

SPECIFICATION forming part of Letters Patent No. 709,939, dated September 30, 1902.

Application filed January 9, 1902. Serial No. 89,081. (No model.)

To all whom it may concern:

Be it known that I, CLARK F. THAYER, a citizen of the United States, residing at Erie, in the county of Erie and State of Pennsylvania, have invented certain new and useful Improvements in Couches, of which the following is a specification.

The object of this invention is to construct a couch embodying the improvements hereinafter more particularly described.

In the accompanying drawings, Figure 1 is a transverse vertical sectional view through a couch, illustrating the mode of construction which embodies my invention. Fig. 2 is a fragmental longitudinal section showing the box-loops in the longitudinal supporting bands and the means of attaching the coil-springs thereto, also showing the clips for securing the zigzag cross-wires to the tops of said springs. Fig. 3 is a fragmental top plan view of a couch of my improved construction. Fig. 4 is a fragmental view in perspective, illustrating the intersection of a longitudinal supporting-band with a transverse supporting-band. This figure shows the depressed box-loops in the longitudinal band, also the means for securing the coil-springs to the bands at their intersections. Fig. 5 is an under side view of a clip for securing the zigzag cross-wires to the tops of the coil-springs. Fig. 6 is a transverse vertical section through the clip illustrated in the last preceding figure and the wires which it secures together. Fig. 7 is a view illustrating the loop at each end of the zigzag wires for connecting said zigzag wires to the longitudinal side wires of the couch.

In the construction of this couch I provide the usual framework A, within which are supported in any suitable manner the longitudinal bands A' and the transverse bands A², both preferably constructed from band iron or steel. The transverse bands A² are straight; but those A', extending lengthwise 45 of the couch, are formed with the box-loops A³ at intervals suitable to receive the transverse bands A², which extend across the couch from one side of the frame A to the other, lying in said depressed loops A³. The spiral springs 50 B are mounted on the bands A' and A², one spring at each point of intersection between

the bands. The lower end of the spring is twisted underneath the longitudinal band A' and over the transverse band A², holding the lower and smaller end of the spring firmly to 55 the bands, and, by reason of the numerous bearing-points of the spring against the bands, supporting the spring securely in an upright position.

Along each side of the couch I provide the 60 longitudinal side wires C for holding the upholstered top of the couch outward in a straight line at the sides thereof. Between these side wires C are placed the transverse wires D, formed zigzag to extend diagonally 65 from one spring to another. At their ends the cross-wires D are provided with the downwardly-extending loops D', adapted to loosely surround the longitudinal side wires C. Two of these wires D are placed between 70 each transverse row of springs and are secured to the tops of the springs by means of a clip E, formed, preferably, of sheet metal and bent to surround the cross-wire D and the wire of the spring. These clips are provided 75 with three tangs—two on one side and one on the other. The side which has two tangs is caused to engage the cross-wires D, they being straightened for a little distance to receive the clips. The single tang on the other 80 side of the clip engages the spring, which on account of its circular form will not permit it to be held in close contact with the straight portion of the zigzag cross-wires D. When a portion of the couch is depressed, as by a 85 person sitting upon it, the side wires C and the springs B at the immediate point where the weight of the person rests are depressed. The loops D' of the cross-wires D permit the 90 side wires C to be depressed without straining the connection between the cross-wires and the side wires, as would be the case were they secured rigidly together. The loops D' also are made long enough, so that the side wires may have some little movement in said 95 loops and may be twisted at an angle with the plane of the tops of the springs without straining the connection between the cross-wires and said longitudinal side wires. The loops may be made longer—that is to say, to 100 extend downward a greater distance than is indicated in the drawings.

I claim as my invention—

In a couch, in combination, a frame; spiral springs supported by the frame; longitudinal side wires; and zigzag cross-wires extending between alternate opposite springs and secured to said springs near the upper ends of the latter, said cross-wires having loops at their ends for surrounding said longitudinal

side wires for providing a sliding and yielding connection between the cross-wires and the side wires.

CLARK F. THAYER.
